UNITED STATES PATENT OFFICE.

HENRY C. KRIETE, OF CHICAGO, ILLINOIS.

RAIL-CUTTING DEVICE.

SPECIFICATION forming part of Letters Patent No. 311,589, dated February 3, 1885.

Application filed March 25, 1884. (No model.)

To all whom it may concern:

Be it known that I, HENRY C. KRIETE, a citizen of the United States of America, residing at Chicago, in the county of Cook and 5 State of Illinois, have invented certain new and useful Improvements in Rail-Cutting Devices, of which the following is a specification, reference being had therein to the accompanying drawings.

10 My invention relates to improved mechanism to be used in connection with steel ingots during their conversion into steel rails. After passing through the blooming and finishing rolls the ingot is formed into one long rail, 15 usually of about one hundred and twenty feet in length, and it becomes necessary to cut such rail into several shorter ones, generally into four of thirty feet each, and it is essential that all the sections should be of a uniform length.

The object of this invention is to provide suitable mechanism by the use of which all the sections of rail will be of uniform length, provision being made for the contraction of 25 the metal. It will be understood that the hotter the rail the more the contraction thereof, and it consequently follows that the first section cut from the long rail will contract more than those subsequently cut, and that 30 such first cut section would be shorter than the subsequent ones if some means were not employed to avoid such difficulty.

For the accomplishment of this end the invention consists of a stopper against which 35 the end of the rail is forced and rests during the operation of the saw, said stopper being provided with a suitable number of projections each of a different thickness. When the first section is to be cut the thinnest or 40 least prominent projection is presented and the rail cut at such a length that upon contraction it will be the proper length—say thirty feet. The stopper being thus turned the next projection is presented and a slightly 45 shorter rail cut, &c.

Reference will be made to the accompanying drawings, in which Figure 1 is a plan view of the stopper, showing part of the rolling mechanism; Fig. 2, a side view thereof, and 50 Fig. 3 an end view of the same.

Like letters refer to like parts in each view.

A represents the stopper, which is mounted upon a shaft, B, in line with feed-rollers C, upon which the rail to be operated upon is moved. The stopper, as herein shown, is 55 constructed for use where it is desired to divide the rail into four sections, and it consists of a hub from which radiate three arms, a, b, and c, each provided with a projection, a' b' c'. Projection a' is of such a thickness and so 60 placed in relation to the cutting mechanism that the section formed when the rail contacts therewith will be exactly thirty feet after contraction, while as the rail grows cooler, it being necessary to cut a shorter section, the 65 projection b' c' are successively presented, the projection b' being of a slightly greater thickness than a', and c' being thicker than b'.

Keyed to shaft B is a cog, d, which meshes 70 with a cog, e, mounted on a stud, and which in its turn meshes with a cog, f. Cog f is keyed to a shaft, g, to the opposite end of which is keyed a bevel-gear, h, which meshes with a similar gear, i, keyed to one end of a 75 shaft, k, upon the opposite end of which is mounted a hand-wheel, l. By this connection it will be seen that the stopper may be revolved to present the different projections in line with the rail by any one operating said 80 hand-wheel. When the rail has been cut it will be understood that the stopper may be turned to allow it to pass between the arms thereof.

What I claim is—

1. In a device for cutting rails, the combination, with suitable cutting mechanism, of a stopper provided with a series of projections of different thicknesses, as and for the purpose set forth.

2. The stopper A, constructed as described, in combination with means for operating it, as and for the purpose set forth.

In testimony whereof I affix my signature in presence of two witnesses.

HENRY C. KRIETE.

Witnesses:

M. J. CLAGETT,
LOUIS NOLTING.
